UNITED STATES PATENT OFFICE.

JOHN BUSHEK, OF ELMHURST, NEW YORK.

MACHINE FOR STRAIGHTENING DISK WHEELS.

Application filed September 4, 1924. Serial No. 735,738.

My invention relates to machines for straightening disk wheels. It pertains particularly to disk wheels of the demountable type in which the feature of demountability is embodied in the construction by bolting the central portion of the disk to a wheel hub flange in such manner that it may be unbolted therefrom without removing the wheel hub from the axle of the vehicle. Such wheels are in very extended use today. The disks are made of comparatively thin steel plate and are most frequently tapered in thickness from the central portion outwardly to the rim. Sometimes, in the process of manufacture, and often in the case of accidents to vehicles on which these wheels are used, these disks are bent and distorted more or less severely. The machine of my invention is used in restoring them to straightened condition.

My invention is an improvement in such machines. Such machines comprise an arbor press, a frontal extension from the base of this press, and a clamp secured to the outer end of this extension shaped to clamp demounted wheels in their central portions and to accommodate the inner flange of the wheel, and positioned on the extension of the base to present the clamped wheels in a plane substantially at right angles to the plunger of the arbor press, and with their rim portions raised a considerable distance above the base and its extension, but below and substantially in line with the plunger or ram of the press. Localized bending pressures are exerted by the ram on the distorted free portions of the wheel on lines substantially parallel to the wheel axis.

My invention concerns the clamping means and its object is to provide an improved means for accommodating the central disk flange which is present on most, if not all, disk wheels, to provide for clamping the wheels both outside up and outside down, in which cases the central flanges project axially oppositely, and to provide for the clamping of wheels having variously dimensioned central portions. The first of these objects, I accomplish by embodying a channel-shaped recess in the face of the clamping means to accommodate the inner flange,

the second of them I accomplish by removably and reversibly arranging the clamping members so that the recess may be presented either from beneath or above the clamped wheel according to whether the wheel is to be clamped outside up or outside down, and the third of these objects I realize by providing a plurality of the clamping members interchangeably related and dimensioned according to the varying dimensions of the central portions of the wheels.

In the accompanying drawings, I show one embodiment of my invention.

Of the drawings:

Figure 1 is a side elevation of the press showing a wheel clamped in position outside up.

Fig. 2 is a similar elevation, in the main, of the clamping means showing a wheel clamped in position outside down.

Fig. 3 is a view like Fig. 2 showing an interchangeable clamping device in use.

Referring first to Fig. 1, the base of the arbor press is designated 10. This base is provided with the frontal extension 11. On the outer end of this extension is a support 12 for the wheel to be operated upon. On the upper end of this support are mounted two clamping plates or disks, 15, 15'. The support 12 and the clamping plates 15, 15' are secured together and to the extension 11 by a central through-bolt 14, provided with a nut 16 on its upper end. The through-bolts may be prevented from dropping out when the nut is removed by any suitable means as, by frictional engagement or any positive securing means (not shown).

The arbor press comprises a heavy, overhanging arm 17, connected with the base 10 and supporting at its outer end a plunger 17, mounted for extended reciprocatory movement toward and from the base 10 and substantially at right angles thereto. Power-multiplying means in the form of rack teeth 18, pinion 19, and a lever 20, arranged for hand operation, are provided for operating the ram or plunger 17.

A wheel, the disk of which is designated 21, is shown clamped in position upon the support 12 between the clamping plates 15, 15'. It is clamped by its central portion, i. e.,

that area which, when the wheel is mounted in place on the vehicle, is clamped upon the hub of the vehicle by bolting to a hub flange. The faces of this portion are trued 5 so that the wheel will run true when fastened to a trued hub. An inner, inturned flange 13 which, when the wheel is clamped upon the hub, acts either to center the wheel upon the hub or to afford additional bearing for 10 the disk upon the hub, or to serve both of these purposes. In any case, the flange stiffens and strengthens the central portion of the wheel and has come to be a general characteristic of disk wheels. This flange I ac- 15 commodate in a channel-shaped, annular recess R in one of the clamping members 15, 15'. This enables the engaging faces of the clamping members to effect clamping contact with the entire area of the central portion of the disk and to hold the same rigidly. 20 In the instance shown, the wheel 21 is shown outside up, the lower clamping member being provided with the recess R. I form these clamping members as disks of substantially the same diameter, equal to the diameter of the central portion, and provide them with central apertures of a dimension to fit and be centered by the through-bolt 14, whereby the members 15, 15' may be re- 25 versed at will and the wheel reversibly clamped in position outside down as shown in Fig. 2. The clamping members 15, 15' are simply removed, reversed in position and replaced to effect this change. Still further, 30 I provide a plurality of clamping members 15, 15', of various dimensions to correspond to the various dimensions of the central portions of different wheels, and form all of the central apertures A through which they are 35 fitted upon the through-bolt 14 of substantially the same dimension, whereby the clamping members are rendered interchangeable. This is illustrated in Fig. 3 in which the clamping members 15, 15' of greater external diameter and greater diameter of recess R are shown in use clamping a wheel of 40 larger size in lieu of the clamping members 15, 15' shown in Figs. 1 and 2.

Customarily, the base 10 of the arbor press 50 is horizontal and the overhanging arm 17' and the ram 17 vertical. The clamping devices 15, 15' are also horizontal and therefore present the wheel to the press in a substantially horizontal plane. Moreover, the 55 clamping members are so positioned on the outer end of the extension 11 as to present the rim 24 of the wheel substantially in line with the ram 17, and the height of the support 12 is such that rim 24 clears the base 60 and its extension 11 by a considerable distance both when the wheel is presented outside up and outside down, as indicated in Fig. 2.

In operation, the wheel is clamped to 65 bring the distorted portion to be operated

upon beneath the ram 17, and the necessary localized applications of pressure to straighten the wheel are effected through the ram 17 and the power-multiplying means 18, 19, 20. The application is substantially 70 parallel to the axles of the wheel. Irrespective of the nature and the degree of the distortion, this method is so effective as practised by this apparatus as to enable one to straighten the most severely distorted wheel 75 in a very brief time.

The features of my invention make it possible not only more effectually and more rigidly to hold the central portions while they are being operated upon, but also the 80 more quickly and effectually to reverse the wheels for curing distortions in opposite directions, and, still further, to operate upon wheels of any make and size in one and the 85 same machine.

Obviously, my invention is capable of numerous modifications without departing in any wise from its generic spirit, and is applicable in any of its embodiments to disk wheel straightening machines of any make 90 or type. I desire to cover in the annexed claims any and all such embodiments and applications.

What I claim is:

1. In a straightening device for a disk 95 wheel having an inner flange, the combination with means shaped to clamp opposite faces of a disk vehicle wheel at the central portion thereof, and recessed to receive the inner disk flange, of an overhanging arm 100 carrying a press reciprocable transversely of the wheel plane for truing said wheel.

2. In a straightening device for a disk wheel having an inner flange, the combination of means recessed to receive the flange 105 and arranged and shaped to clamp opposite faces of a disk vehicle wheel at the central portion thereof both when the wheel is presented outside up and when the wheel is presented outside down, of an overhanging 110 arm carrying a press reciprocable transversely of the wheel plane for truing said wheel.

3. In a straightening device for a disk 115 wheel having an inner flange, the combination of means recessed to receive the flange, shaped to clamp opposite faces of the wheel at the central portion thereof, and reversible to clamp the wheel both when presented outside up and when presented outside 120 down, of an overhanging arm carrying a press reciprocable transversely of the wheel plane for truing said wheel.

4. In a straightening device for disk 125 wheels of differently dimensioned central portions, the combination of interchangeable clamping means for said central portions shaped each to clamp the opposite faces of a central portion of a different wheel, of an overhanging arm carrying a press recipro- 130

cable transversely of the wheel plane for truing said wheel.

5. In a straightening device for disk wheels of different dimensions having differently dimensioned central portions with inner flanges, the combination of interchangeable clamping means shaped to clamp the opposite faces of the central portions of dif-

ferent wheels, and recessed variously to receive the various inner disk flanges, of an 10 overhanging arm carrying a press reciprocable transversely of the wheel plane for truing said wheels.

In testimony whereof, I affix my signature.

JOHN BUSHEK.
